INCANDESCENT ELECTRIC LAMP SOCKET,
LAMP, AND ADAPTER THEREFORAlbert S. Howell, Culver, Ind., assignor to Bell
& Howell Company, Chicago, Ill., a corporation
of Illinois

Application June 27, 1947, Serial No. 757,435

4 Claims. (Cl. 173—357)

1

My invention relates to an incandescent electric lamp socket, lamp, and adapter therefor of the type disclosed in U. S. Patent No. 1,675,554, granted July 3, 1928, on application filed by me, for improvement in Incandescent electric lamp socket, lamp, and adapter therefor, and has for major objects the provision of an improved socket, lamp, and adapter therefor of said type which is of simple construction, which provides for adequate ventilation through the socket and by the base of the lamp, which provides for accurately and rigidly positioning the lamp in the socket both longitudinally and angularly of the lamp, which provides against tilting of the lamp in the socket, which provides for the mounting of the socket on a lamp receiving sleeve of a ventilated lamp house while providing adequate ventilation through the sleeve and socket, and the adapter of which provides for adapting the conventional base of lamps to my invention, the socket of my invention being particularly adapted for the mounting of a lamp in inverted position in a lamp housing.

With these objects in view my invention consists in certain features of novelty in the construction, combination and arrangement of parts by which the said objects and certain other objects, hereinafter appearing, are effected all as fully described with reference to the accompanying drawing, and more particularly pointed out in the appended claims.

In the said drawing—

Figure 1 is a vertical sectional view of the upper portion of a lamp house equipped with an incandescent electric lamp socket and lamp embodying my invention;

Figure 2 is a top plan view of the annular contact of the socket with a lamp installed thereon;

Figure 3 is a perspective view of a portion of the annular contact of the socket showing one of the contact elements thereof;

Figure 4 is a vertical sectional view of the lamp of my invention installed on an annular socket contact of the type shown in the aforementioned patent, the circumferential contact of the lamp being modified as hereinafter described for installation on this socket contact;

Figure 5 is a top plan view of the socket contact and lamp shown in Figure 4; and

Figure 6 is a perspective view of the lamp base adapter of my invention.

Figure 7 is a partial perspective view of another form of the lamp base adapter of my invention.

Referring to Figures 1 and 2, a vertically disposed lamp housing 1 is closed at its upper end,

2

as designated at 2, and a lamp receiving sleeve 3 is disposed within the housing in concentric relation therewith with its upper end spaced downwardly from the closed upper end 2 of the housing.

A metallic cylindrical lamp socket contact ring 4, having a smaller diameter than that of the sleeve 3, is supported from the sleeve in central relation with and in the region of the upper end of the sleeve by means of support studs 5 angularly spaced about the sleeve axis, bushings 6 of insulating material being interposed between the studs and ring for insulating the ring from the sleeve.

The ring 4, see Figures 2 and 3, is provided with two contact element forming recesses 7 and a third contact element forming recess 8 angularly spaced about the axis of the ring in circumscribing relation therewith and extending downwardly from the upper axial face and spaced from the lower axial face of the ring and formed by these portions of the ring being offset radially outward from the ring as by extrusion. The recesses 7 and 8 provide upwardly facing contact surfaces 9, outer wall portions 11, and angularly facing opposing pairs of shoulders 12 limiting the extents of the contact elements angularly of the socket axis, and the recess 8 is of greater extent angularly of the ring axis than the recesses 7 and the shoulders 12 of the recess 8 are consequently spaced a greater extent angularly of the socket axis than the shoulders 12 of the recesses 7 for a purpose hereinafter appearing.

The socket ring 4 is adapted to have the body 13 of an incandescent electric lamp 14 passed downwardly therethrough for the installation of the lamp on the socket and the base of the lamp is provided with a circumferential metallic contact, generally designated at 15, arranged angularly about the base axis and extending laterally thereof outwardly beyond the lamp body and comprising a peripheral contact portion facing axially of the base in the direction of the lamp body and consisting of two contact elements 16 and a third contact element 17 angularly spaced about the axis of the base in circumscribing relation therewith.

The angular spacing of the contact elements 16 and 17 of the lamp base contact corresponds with that of the recesses 7 and 8 of the socket ring and the extents of the contact elements 16 and 17 angularly of the lamp base axis correspond respectively with those of the recesses 7 and 8, the angular extent of the contact element 17

being greater than the contact elements 16, and when the lamp is installed on the socket the contact elements 16 and 17 are respectively engaged in the recesses 7 and 8 and downwardly on the contact surfaces 9, the three point engagement of the lamp base contact with the socket contact ring providing against tilting of the lamp and the lamp being predeterminedly angularly positioned by reason of the angular extent of the contact element 17 being greater than the angular spacing of the shoulders 12 of the recesses 7 so that the contact element 17 may only be received in the recess 8.

The lamp socket also comprises, see Figure 1, a conductive end contact 18 carried on an arm 19 pivotally mounted, as designated at 21, on a support 22 secured on the upper end of the sleeve 3 radially outward of the contact ring, the contact 18 being thus mounted for movement into and out of contact with a usual centrally disposed conductive end contact 23 of the lamp base for installation and removal of the lamp. A spring device 24, associated with the support 22, is operative on the arm 19 to yieldably urge the contact 18 into and normally maintain the same in contact with the end contact 23 of the lamp base and hold the lamp in the socket with the contact 15 of the lamp base in contact with the contact ring 4 of the socket.

The contact 15 of the lamp base, as shown, is provided by the adapter of my invention which is secured to the outer cylindrical conductive member 25 of a usual lamp base of the lamp, the end contact of the lamp base being insulated from the member 25.

The adapter forming the contact 15, see Figures 2 and 6, comprises a hexagonal collar having alternate long and short sides of which the long sides 26 form arms and have their intermediate portions engaged with the cylindrical conductive member 25 of the lamp base and secured therewith as by soldering and the short sides of which form respectively the contact elements 16 and 17, the short side forming the contact element 17 being of greater extent angularly of the collar than the other two short sides forming the contact elements 16. As shown, the adapter is formed of a single strip of sheet metal of appreciably greater width than thickness and disposed with the width thereof extending transversely of the plane of the adapter, the ends of the strip being joined together by means of a tightly fitting dovetail joint as designated at 27 in Figure 6. The arms of the contact 15 which carry the contact elements 16 and 17 are thus of relatively small and large cross sectional extents respectively parallel to and transversely of the plane of the adapter to provide air passage thereby of relatively great area while providing adequate rigidity.

Referring to Figure 1, an air current is passed upwardly between the lamp housing 1 and sleeve 3 and downwardly past the lamp socket and lamp base and within the sleeve for cooling the lamp, it being observed that the skeletal character of the contact 15 permits the free passage of air thereby and within the socket ring 4, free passage of air being also afforded exterior of the socket ring. The lamp housing 1 is removable in a suitable manner for installation and removal of the lamp.

Referring to Figures 4 and 5, the lamp 14 of my invention is shown installed on a prior art socket contact ring 28 comprising an annular metal ring the upper surface of which is counter-

bored to provide an upwardly facing contact surface 29 surrounding the opening thereof, and the ring being provided with a radial slot 31 at the counterbored portion thereof.

5 The lamp is installed on the socket ring 28 in the same manner as before described with the contact elements 16 and 17 of the circumferential lamp base contact engaged downwardly on the contact surface 29 of the socket ring, and in 10 order to predeterminedly angularly position the lamp, the contact element 17 is provided with a lug 32 projecting therefrom in the direction in which this contact element faces and which engages in the slot 31 to angularly position the lamp, the width of the lug being less than the extent of the contact element 17 angularly of the lamp base axis to provide contact surfaces 33 at the sides of the lug, as shown in Figure 7, which engage downwardly on the contact surface 29.

15 Referring again to Figures 1 and 2, the upwardly facing contact surfaces 9 of the recesses 7 and 8 are shown disposed in the same radial plane of the socket axis, and in order that the 20 lamp may be installed in this socket, lamp is equipped with an adapter which is not provided with a lug 32 as shown in Figure 6.

25 While I have thus described my invention, I do not wish to be limited to the precise details 30 described, as changes may be readily made without departing from the spirit of my invention, but having thus described my invention, I claim as new and desire to secure by Letters Patent the following:

35 1. An adapter for an incandescent electric lamp base comprising a conductive contact member of generally annular character adapted to be engaged about an outer cylindrical conductive member of a lamp base and secured therewith 40 and comprising a substantially hexagonal collar having alternate long and short sides and the long sides of which form arms and have their intermediate portions engageable with said cylindrical conductive member for securing thereto and the short sides of which form contact elements providing an interrupted peripheral contact portion facing transversely of the plane of said contact member and said arms being of appreciably greater width than thickness and disposed with the width thereof extending transversely of said plane to provide air passage thereby of relatively great area.

45 2. An adapter for an incandescent electric lamp base comprising a conductive contact member of generally annular character adapted to be engaged about an outer cylindrical conductive member of a lamp base and secured therewith and comprising a substantially hexagonal collar having alternate long and short sides and the long sides of which form arms and have their intermediate portions engageable with said cylindrical conductive member for securing thereto and the short sides of which form contact elements providing an interrupted peripheral contact portion facing transversely of the plane of said contact member and said contact member being formed of a single piece of sheet metal and the material of said arms being of appreciably greater width than thickness and disposed with the width thereof extending transversely of said plane to provide air passage thereby of relatively great area.

50 3. An adapter for an incandescent electric lamp base comprising a conductive contact member of generally annular character adapted to be

engaged about an outer cylindrical conductive member of a lamp base and secured therewith and comprising a substantially hexagonal collar having alternate long and short sides and the long sides of which form arms and have their intermediate portions engageable with said cylindrical conductive member for securing thereto and the short sides of which form contact elements providing an interrupted peripheral contact portion facing transversely of the plane of said contact member and said contact member being formed of a single piece of sheet material of appreciably greater width than thickness and disposed with the width thereof extending transversely of said plane to provide air passage thereby of relatively great area.

4. An adapter for an incandescent electric lamp base comprising a conductive contact member of generally annular character adapted to be engaged about an outer cylindrical conductive member of a lamp base and secured therewith and comprising three triangularly related arms joined at their ends and having their intermediate portions engageable with said cylindrical conductive member for securing thereto

5 and contact elements at the joined ends of said arms and providing an interrupted peripheral contact portion facing transversely of the plane of said contact member and said arms being of appreciably greater width than thickness and disposed with the width thereof extending transversely of said plane to provide air passage thereby of relatively great area.

ALBERT S. HOWELL.
